United States Patent Office.

DANIEL H. SMITH, OF ATTLEBOROUGH, MASSACHUSETTS.

Design No. 4,911, dated May 16, 1871.

DESIGN FOR BRACELETS.

The Schedule referred to in these Letters Patent and making part of the same.

To all persons to whom these presents may come:

Be it known that I, DANIEL H. SMITH, of Attleborough, in the county of Bristol and State of Massachusetts, have invented a new and useful Design for a Bracelet; and do hereby declare the same to be fully described in the following specification and represented in the accompanying drawing, of which—

Figure 1 is a top view,

Figure 2 a side view,

Figure 3 a longitudinal section, and

Figure 4 a transverse section of a bracelet formed in accordance with my design, it being made, as usual, of two semi-elliptical bows, A A, hinged together and provided with a snap-catch, B.

Each portion A is composed of two plates, a b, the

inner one being formed of two flanges or lips, c c, arranged at acute angles to the remainder of the parts, and in other respects as shown. The external parts b, which fit into the space between the two flanges, are corrugated or molded in manner as shown in transverse section, and are held in place by box-caps d d, fixed upon the ends of the said part A.

What I claim as my invention is—

The design or pattern, as shown in cross-section in fig. 4, of the two parts composing each portion A.

DANIEL H. SMITH.
